(57) **CLAIM**

I claim the ornamental design for a water pistol, as shown and described.

DESCRIPTION

FIG. 1 is a perspective view of the water pistol design of this invention.

FIG. 2 is a second perspective view of the water pistol design of this invention.

FIG. 3 is a third perspective view of the water pistol design of this invention

FIG. 4 is a left side elevational view of the water pistol of this invention shown in FIG. 1.

FIG. 5 is a right side elevational view of the water pistol of this invention shown in FIG. 1.

FIG. 6 is a front elevational view of the water pistol of this invention shown in FIG. 1; and,

FIG. 7 is a rear elevational view of the water pistol of this invention shown in FIG. 1.
